(57) CLAIM

The ornamental design for a combined helmet and drink holder, as shown and described.

DESCRIPTION

FIG. 1 is a perspective view of a combined helmet and drink holder in accordance with my new design;

FIG. 2 is a front elevational view thereof;

FIG. 3 is a left side elevational view, the right side elevational view being a mirror image thereof;

FIG. 4 is a top plan view thereof; and,

FIG. 5 is a bottom plan view thereof.

The rear portion of the article not shown in the drawings or described in the specification forms no part of the claimed design.
